DESIGN.

W. H. WILKINSON.
HEATING STOVE.

No. 17,978.

Patented Dec. 20, 1887.

UNITED STATES PATENT OFFICE.

WILLIAM H. WILKINSON, OF ROCHESTER, NEW YORK, ASSIGNOR TO THE CO-OPERATIVE FOUNDRY COMPANY, OF SAME PLACE.

DESIGN FOR A HEATING-STOVE.

SPECIFICATION forming part of Design No. 17,978, dated December 20, 1887.

Application filed October 7, 1887. Serial No. 251,766. Term of patent 3½ years.

To all whom it may concern:

Be it known that I, WILLIAM H. WILKINSON, a citizen of the United States, a resident of Rochester, in the county of Monroe and State of New York, have invented and produced a new and original Design, of which the following is a specification, reference being had to the accompanying photograph, forming part thereof.

10 The stove design is substantially of rectangular or box form.

The stove consists substantially of the ornamental rectangular stand A, rectangular base B, having rounded corners, rectangular sides C C, and back D, rectangular top E, having rounded corners, and cover F, surmounted by an urn, G, upper front piece, H, columns I, upper and lower fenders, K and L, and foot-rest N.

20 The stand A is composed of horizontal ornamental bars b, forming a rectangular inclosure, and feet a at the corners thereof. The feet curl outward at the bottom and are formed at the top and bottom into involute curves and representations of drooping leaves, while the bars each are formed at the middle with a Greek ornament or shell, i, with representations of leaves and scroll-work on either side thereof, as shown, said ornamentations being raised 25 from fields surrounded by narrow bands c.

The base B rests upon the stand A, and has its upper horizontal diedral angles, d, rounded off and formed with raised representations of leaves inclined laterally away from a central 35 clover-leaf or trefoil, e, at the middle of each face.

The sides C are each formed with marginal moldings f upon the field, within which and at the bottom thereof is formed a dolphin, u', 40 from which raised scroll-work g extends upward and surrounds a central tile, h.

The upper front plate, H, is rectangular and formed with marginal moldings f, like those of the sides C, and has an arched opening, k, 45 formed in its lower edge, which opening constitutes the upper part of the main front opening, O, of the stove, through which the interior of the latter is visible. The opening k is surmounted by a frontispiece or canopy, l, 50 upon which is inscribed in raised letters s' the

name of the stove, the convex surface of said canopy—that is to say, the groundwork outside the letters—being chased or fretted, said canopy being arched and formed with an outward swell. Centrally over this canopy the 55 plate H is provided with a tile or design, n, ornamented with a Maltese cross. On either side of said tile is shown in relief a griffin, o, facing the tile, with their fore feet outstretched above and below the tile, their bodies narrowing into involute curves or scroll-work p, with rosettes r added.

The columns I at each side of the opening O are formed with marginal molding f, forming a continuation of the similar molding f 65 of the plate H, and each column is further provided with a circular tile, s, scroll-work t, and a Maltese cross, u, enumerated in their order downward.

The top E overhangs the body of the stove, 70 and is formed with a plain narrow horizontal band, a', below which is an imperforate cove or fillet, b', said top being rounded over at d' on top to a seat, c', for the cover F. At the ends of the top the parts d' are cut with ornamental 75 projections e', as shown, while in front and rear it is carved into raised representations of leaves without perforations.

The cover F rests upon the seat c', it being an oblong dome, perforated as shown, with a 80 rectangular base, the crown of the dome being formed into a circular seat, g', for the urn.

The urn G is formed at its base with a circular beaded band, h', contracted to a small diameter at i' and expanded at k', the exterior 85 of the latter part being covered with representations of tongues of flame, t', pointing upward, the upper points coinciding with the periphery of the urn.

In front of the stove is formed with an upper 90 fender, K, consisting of three horizontal bars, l', curved outward and tied at intervals by vertical bars n', as shown. Below this is the lower fender, L, similarly curved and cut through in ornamental openings. In front of the lower 95 fender is located the arched foot-rest N, formed into involute spirals o' at its ends and with a central ornamental tile or rosette, p', with open scroll-work r' at either side thereof.

What I claim as my invention is—

1. In a design for a stove, the ornamental rectangular stand A, consisting of horizontal bars and feet at the corners, said feet being ornamented by involute curls at the top and bottom and with drooping leaves, said bars being each formed with marginal bands and a shell or lily at the middle thereof, and raised scroll-work and leaves on each side of said shell or lily extending to the involute curls of the feet, substantially as shown.
2. In a design for a stove, the base B, having rounded diedral angles marked with a clover-leaf at the middle of each angle and representations of raised leaves laterally inclined away from said clover-leaves on each side thereof and formed with an arched foot-rest having involute curls at its ends, a rosette at the middle, and scroll-work filling the space between said rosette and said involute curls, substantially as shown.
3. In a design for a stove, the front consisting of an upper plate, H, formed with an arched recess in its lower edge and marginal moldings, and having a central tile over the arch, with griffins on each side of the tile formed with bodies narrowing into raised scroll-work extending down at the ends of the recess, and
- supporting columns with marginal moldings corresponding to the moldings of said upper plate, and further ornamented with rosettes near their upper ends and scroll-work and a Maltese cross at the lower end of each, as shown.
4. In a design for a stove, the urn formed with a circular beaded band at its base, and having the exterior surface of the body or bowl of the urn carved to represent raised tongues of flame pointing upward and reaching to the edge of the bowl, substantially as herein shown.
5. The design for a heating-stove, consisting of the members A and B, with the body of the stove formed with a canopied front and the overhanging top E, having the shape and ornamentation herein shown.
6. In a design for a heating-stove, the flat rectangular side C of the body, formed with a marginal molding all round, a central tile or rosette, a dolphin at the bottom of the panel within said molding, and raised scroll-work above and below said tile or rosette within said molding, substantially as shown.

W. H. WILKINSON.
